UNITED STATES PATENT OFFICE

OSCAR U. ZERK, OF CHICAGO, ILLINOIS

HOSIERY

Application filed February 18, 1929. Serial No. 340,739.

My invention relates generally to ladies' hosiery and the method of making the same, and has for its object the provision of a novel form of hose which, due to its construction, 5 produces an optical illusion of shapeliness of the limb of the wearer.

A further object is to provide a method of making such hosiery.

Other objects will appear from the following description, reference being had to the accompanying drawings, in which

Fig. 1 shows a hose for use by a wearer having disproportionately large ankles;

Fig. 2 shows a hose to be worn by a woman 15 having disproportionately large knees;

Fig. 3 shows a hose adapted to be worn by a woman, the calves of whole limbs are undeveloped;

Fig. 4 shows a hose for wear by a woman 20 whose limbs have overdeveloped calves;

Fig. 5 shows a hose adapted to be worn by a woman who has both overdeveloped calves and large knees; and

Fig. 6 shows a hose adapted for wear by a 25 woman having large ankles and feet.

It has been found that although dark colored hose produce the effect of a slender limb, dark colored hose of a single shade and without a pattern are not appealing to the 30 eye. The optical illusion thus produced by a dark colored hose is frequently undesirable since it not only makes the ankle of the wearer appear smaller but also decreases the apparent size of the calf, which, for limbs having undeveloped calves, is a disadvantage.

It has been attempted to obtain some of the advantages of my invention by knitting portions of the hose adjacent the ankle double thickness. This, however, has the disadvantage in that it shows a sharp break at the line of joining the double knit portion with the single knit portion and thus removes the effect of an optical illusion.

The hose of my invention are adapted to 45 be dyed in practically any desired color as long as the color is one which has a variety of tints and shades or may be dyed in different colors which are preferably such as readily blend into each other.

As shown in Fig. 1, the hose 10, adapted

for wear by a woman having a disproportionately large ankle, will have the ankle portion 12 a dark shade of the color of the hose and the remaining portions of the hose will be dyed lighter tints of the same color. The 55 shading in the drawing indicates the general idea of the proportionate depth of color of the hose. However, the color of the hose fades gradually by practically imperceptible degrees from the darker shade to the lighter 60 tints so that the effect of the hose when worn will be that rather of a shadow than of an actual difference in color between the various 65 portions of the hose.

The optical illusion above referred to, 65 namely, that the darker shades of colors appear to make the object appear smaller than its actual size and that the lighter tints of the color make the object appear larger than its actual size, is thus utilized to produce an 70 appearance of smart shapeliness to the leg of the wearer.

The hose 14, shown in Fig. 2, is in general 75 similar to that shown in Fig. 1 except that the knee portion 16 thereof is of a darker shade than the calf portion 18 and ankle portion 20 thereof, to produce the optical illusion of a knee which is properly proportioned in size as compared to the other parts of the leg.

The hose 22 shown in Fig. 3, is shaded dark 80 at both the knee portion 24 and ankle portion 26 and will thus be effective to produce the illusion of shapeliness on a leg which has an undeveloped calf. As in the previously described hose, the hose 22 is of a single color and the knee and ankle portions 24, 26 are of a very dark shade while the intermediate calf portion 28 and the thigh portion 30 of the hose are of a lighter tint. The depth of the 85 color of the hose varies very gradually from the dark to the lighter portions so that it is impossible to observe a line of demarcation between the two portions.

Fig. 4 shows a hose 32 adapted for wear by 90 a woman having an overdeveloped calf, and the calf portion 34 of the hose is therefore colored a dark shade and the remaining portion of the hose colored the lighter tints. Thus, by producing the optical illusion of a 95

smaller size calf, the limb attains an appearance of shapeliness in which the parts thereof are in artistic proportion.

Fig. 5 shows a hose 36 adapted for wear by a woman having enlarged lower calf muscles and an enlarged knee. Here again the knee portion 38 and the lower calf portion 40 of the hose which cover the parts of the leg which are disproportionately large, are colored with a very dark shade of the dye used to color the remaining portions of the hose and the remaining portions of the hose are colored with lighter tints of the same color.

Fig. 6 shows a hose 42 in which the entire lower foot portion 44 thereof and ankle portion 46 are dyed with the dark shades to improve the appearance of limbs disproportionately large at the ankle and instep.

The hose may be ingrain dyed, that is, the thread dyed prior to knitting, as is well-known in the art. To accomplish the dyeing of the thread to the various depths of color desired, it is preferable to use only one color dye but to permit the thread to remain in the dye a longer period of time where the deeper color is desired. Thus, for example, the thread may be passed at a continuous rate of speed through the dyeing solution and means provided for removing the thread from the solution at any desired point in its travel so that the distance which the thread moves through the solution may readily be varied, thus to change the length of time which the thread remains in the dyeing solution, or the thread may be selectively run through one or more of a plurality of baths of dyes of different color depth or different colors in order to get the shaded effects at the places shown in the drawings.

As an alternative, the thread of which the hose is to be knitted or the completely knitted hose may be sprayed with dye of the desired color to produce the above described type of hose.

When the hose is dyed after knitting it is preferably dyed with a dye of a single color, the shades and tints thereof being obtained by leaving the hose in the dye for different periods of time. I have found that a hose of the type shown in Fig. 6 may readily be made by suspending the hose over a tank of dye and permitting it to slowly, at a practically constant rate of speed, drop into the dye. The toe and ankle portions will thus be immersed for a longer period and will absorb more dye and consequently become a darker shade than the remaining portions of the hose.

The hose shown in the other figures may be dyed in a similar manner by immersing those portions of the hose which are to be colored darker shades first and immersing the adjacent portions at a gradual rate of speed. By thus controlling the length of time which the portion of hose has immersed in the dyeing

solution, the hose may be dyed to obtain the effects illustrated in the different figures of the drawings.

It is extremely desirable in this dyeing operation that the hose be moved gradually and that adjacent incremental portions be immersed only a short time longer or a short time less than the next adjacent portions so as to produce the effect of a gradual shading in the depth of the color without any apparent or noticeable line of demarcation.

Another method of dyeing the hose in accordance with my invention comprises having a vat filled with a liquid or a solution in which the dye does not dissolve and which liquid or solution is heavier than the normal dye solution, and above this liquid or solution having a relatively thin layer of the dyeing solution. In this manner the hose, which may be put on a suitable form, may be passed through the dyeing solution at any desired speed into the inactive or inert liquid or solution to produce any desired shading and tinting effect.

Other methods may of course be used to dye the hose.

While I have shown and described the preferred embodiments of my invention, it will be understood that I do not wish to limit myself to the specific disclosure but that other decorative patterns may be added to the hose shown. For example, clocks, lined or blocked decorative patterns may be added to the portion of the hose covering the heel and ankle. If desired, block or line patterns may also be added to the upper portion of the hose to produce any desired artistic and aesthetic effect.

Having thus described my invention, what I claim as new and desire to secure by Letters Patent of the United States is:

1. As an article of manufacture, a hose adapted to produce the optical illusion of shapeliness of the wearer's leg, substantially the whole of the hose being of one color but having portions thereof of different tints and shades of said color, the portion of the hose which is to cover a part of the wearer's leg at which it is desired to produce an illusion of smallness being of a relatively dark shade and that portion of the hose which is to cover a part of the wearer's leg at which it is desired to produce an illusion of increased size being of a substantially lighter tint, the part of the hose intermediate the shaded portion and the tinted portion varying by substantially imperceptible degrees of color depth from the darkest shade to the lightest tint.

2. As an article of manufacture, a hose having the incremental transverse sections thereof of different color depth, the portions of the hose adapted to cover a part of the leg of the wearer which is of disproportionately large size being shaded the darkest, whereby an optical illusion of shapeliness of

the wearer's leg is produced by the variation in color depth without producing a noticeable line of demarcation of color depth.

3. As an article of manufacture, a hose having the incremental transverse sections thereof of different color depth, the portions of the hose adapted to cover a part of the leg of the wearer which is of disproportionately small size being tinted the lightest, whereby an optical illusion of shapeliness of the wearer's leg is produced by variation in color depth without producing a noticeable line of demarcation of color depth.

4. As an article of manufacture, a hose adapted to produce the optical illusion of shapeliness of the wearer's leg, said hose having portions thereof of different tints and shades, the portion of the hose which is to cover a part of the wearer's leg at which it is desired to produce an illusion of smallness being of a relatively dark shade and that portion of the hose which is to cover a part of the wearer's leg at which it is desired to produce an illusion of increased size being of a substantially lighter tint, the part of the hose intermediate the shaded portion and the tinted portion varying by substantially imperceptible degrees of color variation from the darkest shade to the lightest tint.

5. As an article of manufacture, a hose adapted to produce the optical illusion of shapeliness of a wearer's leg which is unusually large at the ankle and at the knee, said hose having the portions thereof which are adapted to cover the knee and ankle of a relatively dark shade and having the remaining portions thereof of a substantially lighter tint, the part of the hose intermediate the shaded and tinted portions varying by substantially imperceptible degrees of color variations from the darkest shade to the lightest tint.

6. As an article of manufacture, a hose adapted to produce the optical illusion of shapeliness of a wearer's leg which is unusually large at the knee, said hose having the portion thereof which is adapted to cover the knee of a relatively dark shade and the remaining portions of the hose of a relatively lighter tint, the shaded portion blending by substantially imperceptible degrees of color variation from the darkest part of the shaded portion to the tinted portions of the hose.

7. As an article of manufacture, a hose adapted to produce the optical illusion of shapeliness of a wearer's leg which has an enlarged ankle, said hose having the portion thereof which is adapted to cover the ankle of a relatively dark shade and having the remaining portions of the hose adjacent and at each side of the ankle portion colored in substantially lighter tints, the shaded portion of the hose blending by substantially imperceptible degrees of color variation in both directions from the ankle portion from the

darkest shade in the ankle portion to the lightest tints in the remaining portions of the hose.

8. As an article of manufacture, a hose adapted to produce the optical illusion of shapeliness of the wearer's leg, said hose having portions thereof of different tints and shades, the portion of the hose which is to cover the part of the wearer's leg at which it is desired to produce an illusion of smallness being of a relatively dark shade and that portion which is to cover the part of the wearer's leg at which it is desired to produce an illusion of increased size being of substantially lighter tint, the parts of the hose on each side of the darker shaded portion varying by substantially imperceptible degrees of color variation from the darkest shade to the lighter tints.

In witness whereof, I hereunto subscribe my name this 15th day of Febr., 1929.

OSCAR U. ZERK.
